(57) CLAIM

The ornamental design for an ice pack, as shown and described.

DESCRIPTION

FIG. 1 is a front elevational view of the ice pack of the present invention;

FIG. 2 is a rear elevational view of the ice pack of FIG. 1;
FIG. 3 is a left side elevational view of the ice pack of FIG. 1, the right view being a mirror image thereof; and,
FIG. 4 is a top plan view of the ice pack of FIG. 1, the bottom view being a mirror image thereof.
